UNITED STATES PATENT OFFICE

2,424,538

TOY

Samuel L. Beder, New York, N. Y., assignor of
one-half to Irwin F. Mills Associates, New
York, N. Y.

Application November 14, 1945, Serial No. 628,575.

6 Claims. (Cl. 46—151)

1

This invention relates to improvements in structural toy sets and is intended to provide entertainment for young folks in their early years by catering to their developing observation powers as well as intuition.

One of the objects thereof is to provide a fantastic humpty-dumpty toy figure in the form of egg shaped bodies which call for nesting and enclosing as well as posturing for the purpose of playfully acquiring a conception of means of making an egg stand up erect.

A further object thereof is to provide a combination of parts which, by a step by step process of estimating size, shape, form and color and arranging the parts accordingly, leads the child manipulating same to make Humpty Dumpty, in a toy figure structure, stand up erect on either end and cause encased egg-shaped bodies to do the same thing.

A still further object of this invention is to provide a novel lacing toy the important characteristic of which is to simulate the closing of a vest on a toy figure and at the same time prevent dislodgment of contained egg-shaped bodies.

A final object thereof is to provide an egg-shaped toy figure with foot and hat portions inter-changeably adapted to hold the egg-shaped figure erect whether it is the foot or hat portion which rests upon any surface, this being resorted to in order to turn the Humpty-Dumpty toy figure upside down and still show its oval contoured axis in erect position.

With the above and other objects in view my invention consists in the combination, arrangement and details of construction disclosed in the drawings and specification and then more particularly pointed out in the appended claim.

In the drawings, wherein similar reference characters designate similar parts throughout the respective views

Figure 1 is a front elevation of my invention, with all parts encased and closed.

Figure 2 is a perspective view of all parts grouped so as to show manner of interconnecting them.

Figure 3 is a series of side elevational views of variably sized egg-shaped bodies hereinafter described, and

Figure 4 is a vertical sectional elevation of the series of nested eggs.

Referring to the drawings which are merely illustrative of my invention, I disclose an egg-shaped hollow toy figure body consisting of two similarly shaped half sections 10 and 11, each carrying a depending L-shaped flat foot portion

2

which is a web-shaped flat member, the outwardly projecting part of which is shaped like a shoe and will make flat contact with any supporting surface. These foot portions are designated 12 and 13. The two half body sections 10 and 11 are hinged together along confronting edges as at 15 to permit these hollow sections to open and close, and it will be seen that in either of these positions, the foot members 12 and 13 of these sections will hold them in perpendicularly erect posture shown in Figures 1 and 2.

There are depicted upon the complementary sections 10 and 11 a delineation of a face as at 16 of Humpty Dumpty while at 21 arms are also depicted. The effect is to give the toy figure a grotesquely rotund Humpty Dumpty appearance with the caricatural outline of a pedagogue due to mounting, as a head piece upon both sections, a mortar shaped flat piece 23 carrying the usual cap tassel 24, this being done by providing a pintle 25 centrally of the piece 23 and inserting same into a perforation 26 formed in either body section 10, 11, made to receive it.

Vest sections made of pliable material, whether of textile or alkid origin, are provided designated 17 and 18, having their inner edges secured permanently at diametrically opposite points of the closed toy figure, to these sections 10 and 11, while their outer edges are respectively lined with rows of eyelets 19. A lacing cord 20 is threaded properly into both rows of eyelets on both sections 10 and 11, so that when the lacing cord is tied it will draw together the vest sections, causing them to overlap the sides of the figure body as they draw together the sections 10, 11 thereof into abutting flat relationship. If, now it is desired to turn the egg-shaped figure upside down so as to stand it upon the flat cap piece 23 it can readily be done, and again it will be observable that the oval figure stands up erect.

The egg-nesting feature of my invention is carried out by a plurality of sectionally hollow egg-shaped bodies of graduated sizes and varying colors, designated 21, 21a, 21b, 21d, etc. The sectional construction of each of these bodies supplies one of the two sections of each of them with an annular tenon 28 adapted to fit in an annular groove of the mating section, or any similar arrangement. Thus, two sections of any of these hollow bodies can frictionally be closed one on the other, but when separated, permit the next smaller sized sectional oval body to be lodged partially on one section and partially in the closing cover section. Figure 4 shows all such 55 assembled bodies in a snugly nested relationship

to form a single loaded oval unit which can readily be inserted into sections 10 and 11 of the jacket casing forming the toy figure, after which the vests are tied together by the lacing toy. It is now apparent that the vested-egg sectional unit is also resting on its end as well as Humpty-Dumpty himself.

I do not confine myself to the exact details set forth which come within the purview of the appended claims.

What I desire to claim and secure by Letters Patent is:

1. A toy figure consisting of a pair of oppositely arranged complementary figure-body sections designed to have an opening and closing movement, a pair of pliable vest sections respectively carried overlappingly by said figure body sections having rows of eyelets at their free ends, L shaped legs with broad flat bases simulating feet carried by the respective figure body sections adapted to support same in open or closed position, and a lacing cord inserted in the eyelets of both of the vest sections for lacing them in closed relationship to complete the unity of the figure body.

2. A toy figure consisting of an egg shaped body composed of two sections movably connected so as to open and close upon each other, being inscribed with a depiction of a head and body of a human, one of said sections having a perforation at its upper part, a mortar-board shaped cap having a pintle removably fitted into said perforation snugly and frictionally so as to be anchored therein, upon which mortar-board shaped cap the body will rest when placed in upside-down position, a pair of elongated flat feet carried by said respective sections in a plane at right angles to the axes of said sections to support the sections perpendicularly, and means for keeping said sections in closed relationship.

3. An egg-shaped body inscribed so as to depict the head and body of a toy figure, a pair of web-like flat feet disposed at right angles to the axis of said body for supporting same perpendicularly, and a mortar-shaped cap having a pintle designed to be removably inserted into the top of said body to complete the outline of the toy figure upon which mortar-board shaped cap the body will rest when placed in upside-down position.

4. A toy figure consisting of a sectional body-piece providing two parts hinged together so as to be opened to move outwardly and closed in flat contact with each other, a pair of textile material vest sections having their inner edges permanently secured at diametrically opposite points of said body-piece, to said hinged parts and having a row of eyelets each at its outer edge, and a lacing cord inserted lacingly in both rows of eyelets of both vests as a means of effecting the abutting contact of the hinged parts and closing of the vest sections.

5. In combination a pair of oppositely-arranged and hinged toy figure body sections, a pair of flat feet carried respectively by said body sections and adapted when the sections are closed upon each other and the feet brought into proximity to each other to provide a stand for holding the toy figure body erect, and also capable, when they are spread out, and the body sections are in open position to support said sections perpendicularly, a pair of pliable vest sections secured at their inner edges to said body sections so as to be closed in overlapping contact against said body sections, and also acting as handles to close the latter, and means for holding the outer edges of the vest sections in closed relationship across the abutting line of the body sections.

6. A toy structure consisting of a humpty-dumpty simulated egg-shaped hollow body composed of two hinged sections having L-shaped flat feet respectively designed to support them in open or closed position, a plurality of variably sized two-part hollow egg-shaped bodies encased snugly one within the other to provide a single loaded unit insertable into either hinged section as to be encased in both hinged sections when they are in closed position, and lacing means engaging both hinged sections to draw them in a closed abutting relationship.
